Primary Examiner — Darcey E Gottschalk(74) *Attorney, Agent, or Firm* — Fitch, Even, Tabin & Flannery LLP(57) **CLAIM**

The ornamental design for a medical dressing, as shown and described.

DESCRIPTION

FIG. 1 is a top perspective view of a medical dressing, the oblique line shading representing transparency;

FIG. 2 is a partially exploded perspective view thereof as it may appear with release liners removed;

FIG. 3 is an exploded perspective view thereof;

FIG. 4 is an enlarged right side elevation view thereof;

FIG. 5 is an enlarged left side elevation view thereof;

FIG. 6 is an enlarged front elevation view thereof;

FIG. 7 is an enlarged rear elevation view thereof;

FIG. 8 is a top plan view thereof;

FIG. 9 is a bottom plan view thereof; and,

FIG. 10 is a perspective view thereof, with release liners removed, as it may appear when applied to a person.

The oblique line shading shown in FIGS. 1–10 shows transparency.

The small circular broken lines shown in FIGS. 1–3 and 8–10 represent perforations and form no part of the claimed design.

The broken lines in FIG. 10 depict environment that forms no part of the claimed design.
